Patented Mar. 16, 1920

FIG. 2.

FIG. 1.

FIG. 4.

FIG. 3.

Inventor:

Edward H. Anshelm,
By his attorney,
Parker D. Goodey.

UNITED STATES PATENT OFFICE.

EDWARD H. ANSHELM, OF CAMBRIDGE, MASSACHUSETTS.

COMBINATION CIGARETTE AND MATCH CONTAINER.

1,333,695.

Specification of Letters Patent. Patented Mar. 16, 1920.

Application filed November 26, 1918. Serial No. 264,130.

To all whom it may concern:

Be it known that I, EDWARD H. ANSHELM, a citizen of the United States, residing at Cambridge, in the county of Middlesex and 5 State of Massachusetts, have invented new and useful Improvements in Combination Cigarette and Match Containers, of which the following is a specification.

This invention relates to containers especially adapted for containing matches, cigarettes and the like, and has for its object to provide an inexpensive, compact container having a magazine for cigarettes and the like and a separate container for 10 matches, provision being made whereby the cigarettes may be inserted or removed, one at a time, without interfering with the others contained therein, while the matches may be removed without interfering in the least 15 with the cigarettes contained therein, said device being very strong and durable so as to be carried in the pocket without danger of breaking or injuring the cigarettes.

Another object of the invention resides in 25 the means for operating the device to allow the cigarettes to be removed or to replenish the supply of cigarettes.

The invention consists in the combination and arrangement of parts set forth in 30 the following specification and particularly pointed out in the claims.

Referring to the drawings:

Figure 1 is a side elevation, partly in section, of a container embodying my invention.

Fig. 2 is a longitudinal section taken on the line 2—2 of Fig. 1.

Fig. 3 is an end view of the container.

Fig. 4 is a transverse section taken on the 40 line 4—4 of Fig. 1.

Similar numerals refer to like parts in the several views of the drawings.

In the drawings, 1 indicates the outer casing of a container, said casing being preferably cylindrical and provided with a slot 2 extending longitudinally of one side thereof for nearly the entire length of said casing, said slot being substantially the size of a cigarette and constituting an opening 45 through which the cigarettes are inserted into said container or through which they are removed, one at a time, to be used.

Arranged within the casing 1 is a second cylindrical casing 3 disposed substantially concentric with said outer casing 1 and rotatably mounted relatively to said outer casing. The inner casing 3 forms an annular chamber 4 within the outer casing substantially equal in depth to the diameter of a cigarette, and this chamber is adapted to 55 contain cigarettes.

One end of the inner casing 3 is closed by a cap 5 permanently secured to said inner casing, said cap having an annular rim 6 adapted to extend over the adjacent end of 60 the outer casing 1 and revolve loosely thereon. The opposite end of the inner casing 3 is open at 7, and this end is also secured permanently to a cap 8 by solder or other securing means, and the cap 8 also has an 70 annular rim 9, similar to the rim 6, said rims 9 and 6 being turned inwardly toward each other and over their respective ends of the outer casing 1 and have rotatable engagement therewith so that the inner casing 75 3 may be rotated with respect to said outer casing and always maintained in its concentric relation therewith.

As hereinbefore stated, the inner casing is placed within the outer casing a distance 80 equal to the diameter of a cigarette so as to form the annular chamber 4, which is the cigarette magazine. Arranged within the annular chamber 4 and surrounding the casing 3 are two series of separators 10 and 85 11 which form pockets 12 for containing and positioning cigarettes, as shown at A.

These separators are attached to said inner casing to rotate therewith and prevent any circumferential movement of the cigarettes contained within the chamber 4 relatively to the inner casing 3, and furthermore said separators prevent the cigarettes from touching each other. These separators extend for only a short distance lengthwise 95 of the casing 3 and are provided with end pieces 13 and 14 respectively to engage the ends of the cigarettes and prevent them from extending into the portion of said outer casing covered by the annular flanges 6 and 9, 100 which would interfere with the removal of the cigarette from the casing if such movements were allowed.

The outer faces of the annular rims 6 and

.9 are knurled or roughened at 15 to facilitate the rotation of the inner casing relatively to the outer casing when it is desired to aline the pockets 12 with the slot 2, either to insert the cigarette in said container or to remove the same therefrom.

The inner casing 3 is made hollow and constitutes a match receptacle, said matches being inserted in said casing through the opening 7, and a cap 16 is pivoted at 17 to the cap 8 within a depression 18 formed in said cap. Means are provided for maintaining said cap in its normal position, said means embodying preferably a resilient tongue 19 formed from a portion of the material constituting said cap 8 which extends inwardly into engagement with a rib 20 formed upon the eye 21, said rib being disposed upon opposite sides of the axis of the pivot 17 from the cap 16 so as to exert a closing action on said cap.

To facilitate the removal of the cigarettes from the magazine 4, recesses 22 are formed at opposite sides of the slot 2 near the central portion of said slot and in the space between the separators 10 and 11. Through these recesses the fingers may be inserted when the inner casing, with the cigarettes carried thereby, has been rotated so as to present one of said cigarettes into alinement with said opening 2.

The size and capacity of the container may be varied to suit the individual taste. In the present embodiment, however, it contains eight pockets and an ample supply of matches, as shown at B. It is advisable to leave one of the pockets empty, and this pocket is turned so as to aline with the opening 2 of the outer casing, for if a cigarette is placed in every pocket, the pocket alining with said opening would have no means for preventing the cigarette from dropping through said opening 2.

With said empty pocket in alinement with said opening, the other cigarettes in the container will be amply protected by the outer casing and may be carried in the pocket without danger of breaking or injuring the cigarettes therein. To facilitate the scratching of matches, the surface of the cap 16 is roughened or knurled at 23.

Having thus specifically described my invention, what I claim and desire by Letters Patent to secure is:

1. A container for cigarettes, matches and the like having, in combination, an outer cylindrical casing provided with an opening extending longitudinally of one side thereof, a second cylindrical casing disposed within and in concentric relation to said outer casing and forming with said outer casing an annular chamber adapted to contain cigarettes and the like, means disposed within said annular chamber adapted to

separate the cigarettes therein to form 65 pockets, and caps secured to opposite ends of said second cylindrical casing, adapted to close opposite ends of said annular chamber and having rotatable engagement with said outer casing, whereby said casings may be 70 moved relatively to each other to present the pockets in said annular chamber, one at a time, to said opening.

2. A container for cigarettes, matches and the like having, in combination, an outer 75 cylindrical casing provided with an opening extending longitudinally of one side thereof, a second cylindrical casing disposed within and in concentric relation to said outer casing and forming with said outer casing 80 an annular chamber adapted to contain cigarettes and the like, means disposed within said annular chamber adapted to separate the cigarettes therein to form pockets, caps secured to opposite ends of said 85 second cylindrical casing, adapted to close opposite ends of said annular chamber and having rotatable engagement with said outer casing, whereby said casings may be moved relatively to each other to present the 90 pockets in said annular chamber, one at a time, to said opening, and a closure for said second casing.

3. A container for cigarettes, matches and the like having, in combination, an outer 95 cylindrical casing provided with an opening extending longitudinally of one side thereof, a second cylindrical casing disposed within and in concentric relation to said outer casing and forming with said outer 100 casing an annular chamber adapted to contain cigarettes and the like, means disposed within said annular chamber adapted to separate the cigarettes therein to form pockets, caps secured to opposite ends of 105 said second cylindrical casing, adapted to close opposite ends of said annular chamber and having rotatable engagement with said outer casing, whereby said casings may be moved relatively to each other to present 110 the pockets in said annular chamber, one at a time, to said opening, a pivoted closure for one end of said second named casing, and means for yieldingly maintaining said closure in its closed position.

4. A container for cigarettes, matches and the like having, in combination, an outer cylindrical casing provided with an opening extending longitudinally of one side thereof, the central portion of said opening being enlarged, a second cylindrical casing disposed within and concentric with said outer casing and forming with said outer casing an annular chamber adapted to contain cigarettes and the like, the interior of said inner casing constituting a match receptacle, caps secured to opposite ends of said second cylindrical casing adapted to maintain said

second casing in rotatable engagement with said outer casing, means secured to opposite ends of said second named casing within said annular chamber, adapted to form a plurality of pockets, each adapted to contain a cigarette, and a closure for one end of said second named casing.

In testimony whereof I have hereunto set my hand in presence of two subscribing witnesses.

EDWARD H. ANSHELM.
